Inventor,

Edward Paul Belz.
Frankstaaleman
Attorney.

UNITED STATES PATENT OFFICE.

EDWARD PAUL BELZ, OF ATHENS, WISCONSIN.

HARNESS TRACE-CHAIN.

1,346,439.

Specification of Letters Patent. Patented July 13, 1920.

Application filed May 29, 1919. Serial No. 300,780.

To all whom it may concern:

Be it known that I, EDWARD PAUL BELZ, a citizen of the United States, residing at Athens, in the county of Marathon and 5 State of Wisconsin, have invented a new and useful Improvement in Harness Trace-Chains, of which the following is a specification.

This invention relates to chains and particularly to those which are used for traces of draft animals, the said invention having 10 for its object the provision of novel means whereby the links of the chain will present the relatively smooth surface to engage the 15 sides of the draft animal, so that chafing or injury to the animal will be avoided. A further object of the invention is to provide means whereby the chains will afford a yielding action to absorb shock or vibration 20 due to uneven pulling conditions, thus making it possible to produce a metallic trace having yieldable characteristics, while at the same time it will possess strength and durability and prove comparatively inexpensive to produce.

It is furthermore the purpose of the inventor to produce a chain having links which can be assembled after the links are completed and making the chain so that the 30 links may be increased or diminished according to the requirements in practice, by having the links detachable, one from the other.

With the foregoing and other objects in view, the invention consists in the details 35 of construction as well as in the arrangement and combination of parts to be hereinafter more fully set forth and claimed.

In describing the invention in detail, reference would be had to the accompanying 40 drawing illustrating the preferred embodiment of the invention in which—

Figure 1 illustrates a view in perspective of a link embodying the invention.

Fig. 2 illustrates a side elevation of assembled links.

Fig. 3 illustrates a plan view of one of the links.

In these drawings I have shown the links as each comprising a member, preferably a 50 steel wire, bent on itself to form the loop 5 and the shanks 6 and 7, the said shanks having overturned extremities 8 and 9 respectively, whose ends are preferably welded to the shanks so as to form elongated eyes 55 10 and 11 respectively.

The loop portion 5, which in some instances is termed "the bolt part of the link," is offset from the plane of the shanks and might be said to have a lateral curve which terminates on the plane of the eyes of the 60 shanks so that when the links are assembled as shown in Fig. 2, the sides of the links offset the eyes and present flat surfaces which are the inner sides of the chain when in use; in other words, the said inner sides 65 are those which are intended to bear against the sides of the draft animal.

The elongated eyes 10 and 11 are preferably of such dimensions as to permit the insertion of the ends of the shank, one of 70 which may be threaded through the eyes to enable the loop of the link to span the space between the two eyes.

The loop portions 5 of the links are oval and the shanks converge at their ends so that 75 when the links are in assembled relation to each other, there is a relatively great yielding action or resiliency which absorbs shock, which otherwise would be occasioned by hard pulling or jerking.

The construction, operation and advantages will, it is thought, be understood from the foregoing description, and the said advantages will, is is thought, be appreciated by those skilled in the art.

I claim:

1. A chain trace comprising interengaging links, each consisting of a metallic member, with a loop open at one end, and converging shanks, the said shanks having 90 elongated eyes, and the closed end of said loop being shaped to lie out of the plane of the main portion thereof and terminating into alinement with said eyes.

2. A harness chain comprising interengaging links, each of said links consisting of a strip of resilient metal, with a loop open at one end, and shanks having overturned ends forming elongated eyes and the closed end of said loop being shaped to lie 95 out of the plane of the main portion thereof and terminating into alinement with said eyes, the length of said eyes being greater than its width and overturned portion forming the eyes, whereby the end of one link 100 may be inserted in the eye of the contiguous link.

EDWARD PAUL BELZ.
